UNITED STATES PATENT OFFICE.

CHARLES ED. BOBERG, OF FORT WORTH, TEXAS.

BOX.

No. 923,111.

Specification of Letters Patent.

Patented May 25, 1909.

Application filed September 18, 1908. Serial No. 453,619.

To all whom it may concern:

Be it known that I, CHARLES E. BOBERG, a citizen of the United States, residing at Fort Worth, in the county of Tarrant and State of Texas, have invented new and useful Improvements in Boxes, of which the following is a specification.

This invention relates to the class of paper receptacles, and more particularly to boxes adapted for use in the transportation of mail matter, and has for an object to provide a device of the character which may be manufactured at a relatively low figure, and which when in an operative position will provide means to hold the walls of the receptacle locked to prevent tampering with the contents of the receptacle.

A further object of the invention is to provide a receptacle which may be stamped from a single piece of material, and which will include novel means for reinforcing the corners of said receptacle.

With these and other ends in view which will appear as the nature of the invention is better understood, the same consists in the improved construction and novel arrangement and combination of parts which will be hereinafter fully described and particularly pointed out in the claims.

In the accompanying drawings have been illustrated a simple and preferred form of invention; it being, however, understood that no limitation is necessarily made to the precise details therein exhibited, but that changes, alterations and modifications within the scope of the invention may be resorted to when desirable.

In the drawings, Figure 1 is a perspective view of the present invention, Fig. 2 is a transverse section view, Fig. 3 is a detail plan view of the blank.

Referring now more particularly to the drawing, there is shown a receptacle 1 which is formed from a single blank of material as shown in Fig. 3 of the drawing, and which comprises a bottom wall 2 provided with end walls 3 and 4, and side walls 5 and 6 respectively. The end and side walls are connected at the corners of the bottom 2 by web portions 7 for a purpose to be hereinafter described. The side wall 5 carries a flap 8 in which is formed passages 9 and 9^a, and the side wall 6 is provided with a similar flap 10 in which is formed a passage 11 adapted to aline with the passage 9 formed in the flap 8 when the receptacle is in its

folded position. The end wall 3 is provided with a flap 12 having a reduced portion 12^a in which is formed the passage 13 which is also adapted to aline with the passages 6^a 9 and 11. The end wall 4 is provided with a rectangular flap 14 which carries a tongue 15 provided on one side with adhesive material 16.

As shown in Fig. 2, the flap 14 is folded 65 to lie in parallel spaced relation to the bottom 2, the tongue 15 of the flap being bent at right angles and is passed through the passage 11 formed in the flap 10, is afterward passed through the passage 9 and is 70 finally passed through the passage formed in the flap 12. It will thus be seen that the adhesive material upon the tongue 15 may be moistened, and said tongue may be bent at right angles whereby said adhesive material may be permanently engaged with the outer surface of the flap 10 as will be readily understood.

A device as herein set forth and described is extremely simple in construction, may 80 be manufactured at a relatively low figure and by constructing the tongues 16 as herein shown, it effectively serves to hold the walls of the receptacle in a locked position during transportation of said receptacle. 85 The web portions 7 serve as means to prevent the contents of the box from making its escape through the corners, and these web portions also serve to reinforce the receptacle 90 at the corners thereof.

Upon reference to Fig. 1 the tongue 15 after being passed through the passage 9 is passed through the passage 9^a, and if desired, the said tongue may be moistened at its outer end so that it can adhere to the 95 under side of the flap 8.

Having thus described the invention, what is claimed as new, is:—

1. A receptacle comprising a bottom wall, 100 end walls and side walls integral therewith, a web forming an integral connection at each corner of said receptacle between the end wall and its co-acting side wall adapted to fold on itself and reinforce the corner of the receptacle, the end and side walls carrying flaps to form the top of the receptacle, the flaps of the side walls and one end wall having slots alining with each other and the other end wall having a strap struck from the central portion thereof and projected through the slots of the other flaps to hold the receptacle closed. 110

2. A receptacle comprising a bottom wall, end walls, side walls, said receptacle having web portions connecting the side with the end walls, flaps carried by said end and 5 side walls, a plurality of said flaps being provided with alining passages, and one of said side wall flaps having a second passage therethrough and a locking tongue carried by one of said flaps threaded through said 10 alining passages and projected through said second passage to hold said receptacle closed.
3. A box formed of a single piece of material and comprising a bottom wall, side and end walls, flaps on said side and end

walls folded upon each other to lie in parallel spaced relation to the bottom to form the top and three of said flaps having alining slots co-extensive in width with said slots and curved on one side struck from the central portion of one of said flaps and projected through all the other flaps to hold the receptacle closed. 15

In testimony whereof I affix my signature in the presence of two witnesses.

CHARLES ED. BOBERG.

Correction in Letters Patent No. 923,111.

It is hereby certified that in Letters Patent No. 923,111, granted May 25, 1909, upon the application of Charles Ed. Boberg, of Fort Worth, Texas, for an improvement in "Boxes," an error appears in the printed specification requiring correction, as follows: In line 18, page 2, after the word "slots," first occurrence, the words *and a tongue* should be inserted; and that the said Letters Patent should be read with this correction therein that the same may conform to the record of the case in the Patent Office.

Signed and sealed this 15th day of June, A. D., 1909.

[SEAL.]

C. C. BILLINGS,
Acting Commissioner of Patents.

2. A receptacle comprising a bottom wall, end walls, side walls, said receptacle having web portions connecting the side with the end walls, flaps carried by said end and 5 side walls, a plurality of said flaps being provided with alining passages, and one of said side wall flaps having a second passage therethrough and a locking tongue carried by one of said flaps threaded through said 10 alining passages and projected through said second passage to hold said receptacle closed.
3. A box formed of a single piece of material and comprising a bottom wall, side and end walls, flaps on said side and end

walls folded upon each other to lie in parallel spaced relation to the bottom to form the top and three of said flaps having alining slots co-extensive in width with said slots and curved on one side struck from the central portion of one of said flaps and projected through all the other flaps to hold the receptacle closed. 15

In testimony whereof I affix my signature in the presence of two witnesses.
